UNITED STATES PATENT OFFICE.

ALEXANDER S. SPIEGEL, OF CHICAGO, ILLINOIS, ASSIGNOR TO THE ATTRACTOGRAPH COMPANY, OF CHICAGO, ILLINOIS, A CORPORATION.

ADVERTISING APPARATUS.

957,120.

Specification of Letters Patent.

Patented May 3, 1910.

Application filed March 22, 1909. Serial No. 485,015.

To all whom it may concern:

Be it known that I, ALEXANDER S. SPIEGEL, citizen of the United States, residing at Chicago, Illinois, have invented certain new and useful Improvements in Advertising Apparatus, of which the following is a specification.

My invention is an improvement on the class of advertising apparatus made the subject of Letters Patent 911561, granted to me February 2, 1909. In this patent there is disclosed a screen member having arranged upon its face parallel opaque lines with intervening transparent spaces, and in rear of the screen member is a movable member carrying designs which show through the clear spaces of the screen member as the movable member is reciprocated.

It is the object of the present invention to utilize the same screen member and the same movable member, but to make the sign more efficient by enlarging its usefulness both for day use and night use. It is frequently desirable to have attractive designs or symbols on the screen plate clearly observable as a daylight sign without depending upon illuminating means, and at the same time it is desirable that when used at night the designs or symbols upon the screen plate shall not interfere with the disclosure of the designs or symbols carried by the movable member, as these appear through the clear spaces. Further, it is important that when the sign is used as a daylight sign that the designs carried by the movable member shall not interfere with the clearness of the design carried by the screen member. In the present case I have provided a construction and arrangement which permits of the use of the sign either in the daylight or at night, with or without illumination, and though a multiplicity of designs may be provided for they do not interfere or cause confusion one with the other. This is accomplished by arranging the design or symbols carried by the screen member in parallel lines carried upon the opaque lines so that when the sign is illuminated the designs or symbols upon the opaque lines of the screen member are not seen, but practically disappear or dissolve as the light appears, the symbols or designs of the back plate appearing through the clear spaces and showing as if there was but one design. As the plate is moved or re-

ciprocated, other designs appear through the clear spaces in succession. In order that the design upon the rear plate shall not show through the clear spaces in the day time and thus be confused with the permanent sign 60 upon the screen member, I make the clear spaces translucent so that unless there is an illumination back of the movable member the designs carried thereby do not show through what I have termed, the "clear 65 spaces". By "clear spaces" it will be understood that I mean spaces that are transparent, open or translucent.

In the accompanying drawing, Figure 1 is a face view of a screen plate carrying a design or symbol. Fig. 2 is a view of the movable plate carrying two designs, and Fig. 3 is a sectional view taken horizontally through the sign.

The screen member is shown at A, and 75 preferably is made of some transparent material having opaque lines upon its surface, the intervening spaces being transparent or translucent, preferably translucent.

I do not limit myself to a screen member 80 made of transparent material as it may be made of metal, paper or other material with the opaque lines formed by bars and the spaces between being either open or covered with a translucent material. The parallel 85 opaque lines are shown at B and the intervening spaces at C.

In rear of the screen member is a member D, which may be movable or stationary. If stationary it serves as a back 90 ground, and preferably contains a color scheme observable through the clear spaces. When made movable as in my patent referred to, it carries a number of designs upon its face made up of parallel lines, and 95 these designs may be independent of a back ground or in addition thereto. By making the designs of parallel lines the movement of the plate brings different designs in succession in line with the clear spaces in the 100 screen member and thus gives a moving picture effect as described in my patent referred to.

My present invention aims not only to secure the effectiveness of the sign in the night 105 time by the aid of illumination, but to utilize it as a daylight sign as well, and to this end I place a permanent design upon the screen member as indicated by the word "China." In order that this sign may not 110

2
be observable, however, at night when the light brings out the designs carried by the movable plate I make the sign of parallel lines and locate these lines on the opaque lines so that the light showing through the clear spaces causes the lines upon the opaque lines to dissolve or disappear to the observer. In order further, to prevent the designs upon the back plate from showing through the clear spaces in the day time I 5 form the clear spaces of translucent material or of some material just sufficient to conceal the designs on the rear plate, except when these designs are brought out by 10 the use of an illuminating medium.

I may use the screen member with the design thereon with a movable member or with a stationary member in rear thereof. I may also use a screen member with a design thereon, and have a stationary rear member with a color scheme as a back 15 ground, and with or without a design, or the movable member may carry a design without a back ground, or there may be an intermediate plate having a design with a back ground in rear thereof. Where the same plate carries both the design and the background the design is on the front face and the back ground on the rear face.

20 30 What I claim is:

1. In combination in an advertising de-

vice, a member provided with opaque lines and intervening spaces, a design carried upon the opaque lines and a second design showing through the intervening spaces, 35 substantially as described.

2. In combination with a member provided with opaque lines and intervening spaces, a design made up of parallel lines and carried wholly by the opaque lines, the 40 intervening spaces being made translucent, a second member in rear of the first carrying a design, and means for illuminating the design on the rear member to cause it to show through the translucent spaces, sub- 45 substantially as described.

3. In combination with a screen member having opaque lines, a design or symbol made up of parallel lines carried on the opaque lines, intervening translucent spaces, 50 a member in rear of the screen member carrying a design or symbol, means for giving movement to one member in relation to the other and illuminating means for causing the design on the rear member to show 55 through the translucent spaces, substantially as described.

ALEXANDER S. SPIEGEL.
